UNITED STATES PATENT OFFICE.

JACOB K. ALTEMUS, OF PHILADELPHIA, PENNSYLVANIA.

YARN-WINDING MACHINE.

Application filed October 28, 1926. Serial No. 144,734.

This invention relates to improvements in 5 yarn winding machines and has for an object the provision of a novel inexpensive and efficient mechanism to prevent the cutting of the yarn guiding parts by the yarn by causing the yarn to be reciprocated laterally of its path of travel as it passes its guiding parts, thereby distributing the wear over a wide area of the yarn guides.

10 Another object of the invention is to provide a novel means for effectively rectifying the yarn strand on its way from the source of supply thereof to the tension device by removing from the yarn all kinks and loops 15 before the yarn enters the tension device.

The invention consists in the novel construction, combination and arrangement of parts hereinafter described and claimed.

In the accompanying drawings illustrating 20 the invention,

Figure 1 is a front view of a yarn winding machine embodying my invention, part of the central portion of the machine being broken away.

25 Figure 2 is a top view of one end portion of the machine.

Figure 3 is a transverse, vertical section through the machine.

30 Figure 4 is a sectional detail, showing the lever for reciprocating the longitudinally movable bar carrying the yarn engaging parts, and adjuncts.

Figure 5 is a detail showing one of the 35 yarn guides.

Figure 6 is an enlarged top view of a part of the longitudinally-movable bar and the 40 yarn engaging parts carried thereby.

Figure 7 is a transverse section through the yarn rectifying device, enlarged.

45 Referring to the drawings, the main frame or support of the machine includes end standards 2 connected by horizontal bars 3 and 4.

A cone receiving and rotating spindle 5 is mounted to rotate in a bearing 6 forming part of a bracket 7 which is secured to and projects from frame bar 4. The lower end portion of the spindle 5 is provided with a whirl disc 8 which rests normally on the leather covering 9 secured to the periphery of a driving wheel 10. The driving wheel 10 is carried by a horizontal shaft 11 which extends between and is journaled in bearings on the standards 2. The shaft 11 constitutes the main driving shaft of the machine and it is provided with a suitable

sprocket wheel or gear 12 by means of which it may be driven from a suitable motor.

The machine is provided with a vertically reciprocable builder frame or support 13 comprising a horizontal rail 14 and vertically arranged, parallel shafts or rods 15 connected to and extending downwardly from the respective end portions of the rail 14. The shafts or rods 15 are slidable in 60 bearings 16 on the end standards 2, and their lower end portions are provided with brackets 17 carrying rollers 18 which rest upon cams 19 on a horizontal shaft 20. The shaft 20 extends between and is journaled in 65 bearings on the end standards 2 and it is driven by gearing 21 interposed between it and the driving shaft 11 as clearly shown in Fig. 1. The cams 19 are shaped as shown in Fig. 2 to effect the desired up and down 70 movements of the builder frame 13 during the operation of the machine. The construction and operation of the parts thus far described are common and well known in this art and, therefore, it is believed that 75 no detail description thereof is necessary herein.

The upper end portion of the winding spindle 5 is adapted to carry a cone 22 or other suitable core to receive the yarn to be 80 wound thereon; and, the upper portion of the machine has a bracket 23 secured thereon and provided with a stem 24 adapted to receive a cone of yarn 25 or other suitable source of supply of yarn to be delivered to 85 the cone 22 to be wound thereon.

The strand of yarn 26 from the cone 25 or source of supply is drawn upwardly therefrom to and through a yarn rectifying device 27, thence to and through a yarn 90 guide 28, thence to and through two pairs of tension discs 29, thence to and through a yarn guide 30, thence over an emulsion applying roller 31, thence to and around a guiding rod 32, and thence down to and 95 through a yarn guide 33 from which it is delivered to the cone 22.

The yarn guide 33 is supported by an arm 34 which projects from a carrier 35 carried by a builder screw 36 which rises fixedly 100 from the builder frame bar 14; and, during the winding operation, the yarn guide 33 is raised and lowered by the builder frame 13 to the extent of the space between the position of the yarn guide 33 shown by 105 full lines in Fig. 1 and the position thereof shown by dot-and-dash lines in

Fig. 1, and gain movements are imparted to the yarn guide 33 by mechanism similar to that shown and described in my Letters Patent No. 1,493,721 dated May 13, 1924.

6 The pairs of tension discs 29 are of usual construction for applying tension to the yarn and they and the yarn guides 28 and 30 are carried by a suitable bracket 37 secured to the upper portion of the main 10 frame of the machine.

15 The yarn rectifying device 27 comprises sinuously formed round wire forming a series of connected arms 38 which diverge outwardly in alternate succession from a 20 yarn passage 39 formed by and between them, as shown in the drawings. One end of the wire forming the yarn rectifying device is secured to a post 40 rising from the bracket 37.

25 20 I have discovered that by employing a yarn rectifying device related to the source of yarn supply 25 and the tension discs 29, as illustrated in the drawings, I am enabled to straighten the yarn strands and remove all 30 objectionable loops therefrom without placing any harmful tension thereon so that when the yarn reaches the tension discs 29 there will be no danger of the discs stripping or displacing one or more of the threads or filaments relatively to the others and thereby forming thread or filament loops on the sides of the yarn, when yarns composed of loosely twisted threads or filaments are being wound.

35 40 The emulsion applying roller 31 extends longitudinally of the machine with its lower portion in a longitudinally extending emulsion supplying trough 41 which is supported by end brackets 42 of the machine frame. The roller 31 is carried by a shaft 43 having its bearings in the end walls of the trough 41. The shaft 43 and roller 31 are rotated by a belt 44 which passes around suitable pulleys 45 and 46 on the shafts 20 45 and 43, respectively, so that during the operation of the machine, the yarn strand 26 passing over the roller 31 will be oiled by the film of emulsion on the roller. The upper portion of the roller is being constantly 50 supplied with a thin film of emulsion from the emulsion contained within the trough 41 and into which the lower portion of the roller extends.

55 60 The yarn guiding rod 32 over which the yarn strand 26 passes after it leaves the emulsion roller 31, extends longitudinally of the roller 31 and has its end portions supported by bearings 47 on the trough 41. This rod 32 is formed of glass or other suitable wear resisting material.

65 Extending longitudinally of the trough 41 is a horizontally arranged bar 51 supported by grooved rollers 49 in a manner to permit the bar to be longitudinally reciprocated.

65 The rollers 49 are journaled on brackets 50

on the trough 41. The bar 51 is reciprocated by a lever 52 which is fulcrumed at 53 on a bracket 54 projecting upwardly from one of the end standards 2 of the machine frame. The lower arm 55 of the lever 52 70 has a cam slot 56 formed therein into which extends a pin 57 projecting from the builder frame 13, whereby, when the builder frame is raised and lowered, the pin 57, working in the slot 56, will rock the lever 52 back 75 and forth. The upper arm 58 of the lever 52 is connected by a link 59 to the bar 51 to reciprocate the bar 51 when the lever 52 is rocked under the influence of the builder frame 13. The arm 58 of the lever 52 is 80 made in two parts which are longitudinally 85 slideable relatively to each other and which may be secured in different position of adjustment by a suitable bolt-and-slot connection 60, to increase or decrease the distance between the lever fulcrum 53 and the link 57 and thereby vary the extent of movement of the bar 51.

90 The bar 51 carries a bracket 61 which is secured thereto by means of a screw 62 passing through a slot in the bracket 61 and screwed into the bar 51. By loosening the screw 62, the bracket 61 may be adjusted longitudinally of the bar 51 within certain limits. The bracket 61 carries a yarn engaging roller 63 adjacent to one side of the yarn strand extending downwardly from the rod 32 to the yarn guide 33 and adjacent to the same side of the yarn strand extending between the yarn guide 33 and 100 the cone 22 is a vertically arranged bar 64, the upper end of which is secured to a bracket 65 carried by the bracket 61. The bracket 65 is secured to the bracket 61 by means of a screw 66 which extends through 105 a horizontal slot in the bracket 65 and enters the bracket 61 and permits the bar 64 to be adjusted horizontally with respect to the bracket 61 and roller 63 toward and from one side of the yarn strand 26. The roller 63 may be formed of porcelain, glass or other suitable wear resisting material and the bar 64 may be constructed of steel or other suitable wear resisting material. The bar 64 has a vertically-extending, thread-engaging 110 surface 67 which extends throughout and beyond the entire distance of vertical travel of the yarn guide 33 during its traverse and gain movements in building yarn upon the cone 22, during the winding operation, so 115 that the yarn 26 extending between the yarn guide 33 and the cone 22 may be engaged by the bar 64 in all positions of the yarn guide 33.

120 During the winding operation the pull of 125 the cone upon the yarn 26 holds the yarn against the roller 63 and bar 64 as they are moved from the position shown by full lines in Fig. 1 to the position shown by dot-and-dash lines therein and back again. Thus the 130

yarn 26 is caused to move back and forth laterally of its line of travel over the broad wearing surfaces of the yarn guides 30 and 33 and the yarn guiding rod 32, thereby distributing the wear over broad areas and preventing the cutting of these parts by the friction of the yarn thereon.

The strand of yarn 26 passes between the parallel bars 70 of a suitable thread cleaning and knot catching device as the yarn passes from the yarn guide 33 to the cone 22.

In practice the machine is constructed to accommodate a large number of winding spindles 5 each of which is supported by a bracket on the frame bar 4 and is actuated from the shaft 11 similar to the single spindle 5 shown in the drawing; and each spindle is provided with yarn supplying and guiding parts the same as are herein illustrated for the single spindle 5, the bar 51 serving as a common supporting and actuating means for the laterally movable yarn guiding parts of all the spindles.

25 I claim as my invention:

1. In a yarn winding machine, the combination of a supporting frame, a winding spindle adapted to carry a yarn receiver, means to rotate the spindle, a device for supplying yarn, means to guide yarn from said device to a receiver carried by the spindle, said means including a vertically reciprocable builder frame, means to reciprocate the builder frame and a part against which the yarn bears during its travel, a horizontally-extending, longitudinally-reciprocable bar, means to support and guide the bar, an element carried by the bar adjacent to the yarn path and adapted to move the yarn transversely of its line of travel relatively to said part when the bar is actuated, and means operated by the builder frame to reciprocate the bar.

2. In a yarn winding machine, the combination of a supporting frame, a winding spindle adapted to carry a yarn receiver, means to rotate the spindle, a device for supplying yarn, means to guide yarn from said device to a receiver carried by the spindle, said means including a vertically reciprocable builder frame, means to reciprocate the builder frame and a part against which the yarn bears during its travel, a horizontally-extending, longitudinally-reciprocable bar, means to support and guide the bar, an element carried by the bar adjacent to the yarn path and adapted to move the yarn transversely of its line of travel relatively to said part when the bar is actuated, and a lever actuated by the builder frame and operatively connected to the bar to reciprocate the same.

3. In a yarn winding machine, the combination of a supporting frame, a winding spindle adapted to carry a yarn receiver,

means to rotate the spindle, a device for supplying yarn, means to guide yarn from said device to a receiver carried by the spindle, said means including a vertically reciprocable builder frame, means to reciprocate the builder frame and a part against which the yarn bears during its travel, a horizontally-extending, longitudinally-reciprocable bar, means to support and guide the bar, an element carried by the bar adjacent to the yarn path and adapted to move the yarn transversely of its line of travel relatively to said part when the bar is actuated, a lever having a cam slot therein and being operatively connected to the bar to reciprocate it when the lever is actuated, and a part projecting from the builder frame and into said cam slot to actuate the lever when the builder frame is reciprocated.

4. In a yarn winding machine, the combination of a supporting frame, a winding spindle adapted to carry a yarn receiver, means to rotate the spindle, a device for supplying yarn, mechanism for delivering yarn to a receiver carried by the spindle, said mechanism including a vertically-reciprocable builder frame, a yarn guide carried by the builder frame and arranged to deliver yarn to said receiver in a direction transversely of the axis of rotation of the spindle, and means to reciprocate the builder frame, means for directing yarn from said device to said guide, a vertically extending bar adjacent to the path of yarn delivered from said guide and arranged to move yarn delivered from the guide transversely of the line of travel of the yarn relatively to the guide at different elevations thereof when the bar is reciprocated horizontally, and means to reciprocate the bar horizontally.

5. In a yarn winding machine, the combination of a supporting frame, a winding spindle adapted to carry a yarn receiver, means to rotate the spindle, a device for supplying yarn, mechanism for delivering yarn to a receiver carried by the spindle, said mechanism including a vertically-reciprocable builder frame, a yarn guide carried by the builder frame and arranged to deliver yarn to said receiver in a direction transversely of the axis of rotation of the spindle, and means to reciprocate the builder frame, means including a yarn guide spaced above the first named yarn guide for directing yarn from said device to the first named guide, a vertically extending bar adjacent to the path of yarn delivered from the first named guide and arranged to move yarn delivered therefrom transversely of the line of travel of the yarn relatively to the first named guide at different elevations thereof when the bar is reciprocated horizontally, means to reciprocate the bar horizontally, and means movable with said bar to move yarn delivered from the second named guide

transversely of the line of travel of the yarn relatively to the second named guide.

6. In a yarn winding machine, the combination of a supporting frame, a winding spindle adapted to carry a yarn receiver, means to rotate the spindle, a device for supplying yarn, means to guide yarn from said device to a receiver carried by the spindle, said means including two spaced yarn guides positioned to change the direction of travel of the yarn, two spaced elements adapted to move the yarn transversely of its line of travel relatively to both guides when said elements are actuated, and a common means for actuating said elements.

7. In a yarn winding machine, the combination of a supporting frame, a winding spindle adapted to carry a yarn receiver, means to rotate the spindle, a device for supplying yarn, a tension device, means to guide yarn from the first named device to the tension device, means to guide yarn from

the tension device to a receiver carried by the spindle, the last named means including a part against which the yarn bears during its travel, and means to move the yarn transversely of its line of travel relatively to said part.

8. In a yarn winding machine, the combination of a supporting frame, a winding spindle adapted to carry a yarn receiver, means to rotate the spindle, a device for supplying yarn, a tension device, a yarn rectifying device for receiving yarn from the first named device and delivering the yarn to the tension device and having a series of connected arms diverging outwardly in alternate succession on the respective sides of a yarn passage formed by and between them, and guiding means for receiving yarn from the tension device and delivering it to a receiver carried by the spindle.

In testimony whereof I affix my signature.

JACOB K. ALTEMUS.
